Primary Examiner — Karen E. Eldridge Powers*Assistant Examiner* — Jasmine Mlinarcik(74) *Attorney, Agent, or Firm* — Michael J. Feigin, Esq.; Feigin & Fridman(57) **CLAIM**

The ornamental design for a foam hair brush, as shown and described.

DESCRIPTION

FIG. 1 shows a top perspective view of a foam hair brush. FIG. 2 shows a bottom perspective view thereof.

FIG. 3 shows a top plan view thereof.

FIG. 4 shows a left side elevation view thereof.

FIG. 5 shows a bottom plan view thereof.

FIG. 6 shows a right side elevation view thereof.

FIG. 7 shows a back side elevation view thereof; and,

FIG. 8 shows a front side elevation view thereof.

The broken lines define the bounds of the claimed design and form no part of the claimed design.

1 Claim, 5 Drawing Sheets(56)
